UNITED STATES PATENT OFFICE.

JAMES E. ARCHER, OF CHICO, CALIFORNIA.

APPARATUS FOR RIVETING CLOTH, LEATHER, AND SIMILAR MATERIAL.

1,023,061.

Specification of Letters Patent.

Patented Apr. 9, 1912.

Application filed June 6, 1910. Serial No. 565,212.

To all whom it may concern:

Be it known that I, JAMES E. ARCHER, a citizen of the United States, residing at Chico, in the county of Butte and State of California, have invented certain new and useful Improvements in Apparatus for Riveting Cloth, Leather, and Similar Material, of which the following is a specification.

10 The hereinafter described invention relates to an apparatus for the securing of rivets in cloth, belting, and other pliable material, but more particularly in the securing of rivets in connection with the work 15 of manufacturing riveted overalls and harness work; the object of the invention being to dispose of the hand work at present employed for puncturing the cloth or material to be riveted, placing the rivets there- 20 through, and securing the same by upsetting or heading the projecting end of the rivet stem after the placing of a washer thereon and, by so dispensing with the hand work of riveting, materially reducing the 25 cost incident to such riveting and facilitating the work thereof, and increasing the factory output of riveted material of the character described.

To comprehend the invention reference 30 should be had to the accompanying sheets of drawings, wherein—

Figure 1 is a sectional side elevation of the improved apparatus. Fig. 2 is a broken top plan view of the mechanism disclosed by Fig. 1 of the drawings. Fig. 3 is a side elevation of the apparatus viewed from the opposite side to that illustrated by Fig. 1 of the drawings, disclosing the container for the rivets, the means for imparting rotation thereto, and the feed tube or reservoir for the rivet washers. Fig. 4 is an enlarged broken detail plan view of the rivet container and runway for delivering rivets to the rivet clamp. Fig. 5 is an enlarged broken detail side elevation of the features contained in Fig. 4 of the drawings. Fig. 6 is a front end elevation of the apparatus, the frame being sectioned on line *a—a* Fig. 1 of the drawings, and viewed in the direction of the arrows. Fig. 7 is a sectional end view taken on line *b—b* Fig. 1 of the drawings, and viewed in the direction of the arrows. Fig. 8 is a detail view of the drive wheel and the cam clutch shoe for placing 55 the same into locked engagement with the

operating shaft of the apparatus. Fig. 9 is an enlarged broken detail sectional view of the rivet clamp jaws and the plunger rod for operating the same. Fig. 10 is an enlarged plan view of the clamp jaws and 60 the cam fingers for controlling the same. Fig. 11 is an enlarged broken detail sectional view disclosing the mechanism for feeding forwardly the washers for the rivets. Fig. 12 is a broken detail plan view 65 of the devices illustrated by Fig. 11 of the drawings. Fig. 13 is an enlarged broken detail view illustrating the material in position to receive a rivet, a rivet placed there- 70 through, a washer fitted to the stem thereof, and the actuating parts in position for upsetting the stem of the rivet. Figs. 14, 15, and 16 are detail views of two of the actuating cams and the rolls working in the irregular grooves thereof.

In the drawings, the numeral 1 is used to designate any suitable form of a hollow supporting base casting for the apparatus, from which springs an upwardly ex- 80 tended forwardly projected bracket arm 2. Through the base casting is extended an operating shaft 3, which is driven by a drive belt, not shown, working over a drive pulley 4, loosely mounted on the projecting end of the operating shaft 3, Fig. 1 of the 85 drawings. This drive pulley is placed into and out of locked engagement with the operating shaft 3 by means of the cam clutch shoe 5, pivoted at its inner end to the upper end of the arm 5', which arm is keyed to 90 the operating shaft 3. This shoe is located to frictionally engage the under face of the rim of the drive pulley 4, and the outer end thereof is held normally against the face of the pulley's rim by the spring held plunger 95 5², which works through an ear 5^a project- 100 ing from the arm 5', and is held outwardly by the pressure of the spring 5^b, Fig. 8 of the drawings. On a downward movement of the foot treadle 6, which is connected to a crank arm 7, projecting from a rock shaft 8, by means of a link connection 8', the crank arm 9 is thrown to retract the spring held clutch rod 9', Figs. 1 and 3 of the 105 drawings. As this plunger rod is retracted, the free end of which normally lies within the path of the clutch cam shoe 5, the shoe 5 is released and forced into frictional engagement with the drive pulley 4, for transmitting its rotation to the operating shaft 110

3. The moment pressure is removed from the foot treadle 6, the compressed spring 9² exerts itself and forces outwardly the clutch rod 9' to place its free end in the 5 path of the frictionally locked cam shoe 5, which is engaged thereby and depressed to release the drive pulley 4. On the said operating shaft 3 a plurality of cams 10, 10', and 10² are secured, which operate respectively, as hereinafter described, and in the manner mentioned, the awl for puncturing the cloth or material to be riveted, the reciprocating slide for receiving and feeding forwardly the washers for the rivets, the rivet 10 receiving and placing mechanism, the tool for applying the washers onto the stem of the rivets, and the hammer mechanism for heading or upsetting the end of the rivet projecting below the washer. While these 15 various parts operate successively and in the order named, the action of each is so quickly accomplished that to all intent and purpose they seemingly operate simultaneously.
- 20 25 For a clear understanding of the working of the various parts of the apparatus, each will be described in the order named, presuming the operating shaft to be held locked to the drive pulley, for the various mentioned parts perform successively the work required thereof during one complete revolution of the said drive pulley.
- To a post 2' upwardly projected from the 30 overhang portion of the bracket arm 2 is fulcrumed an operating lever, comprising a member 11 and an independently fulcrumed adjustable extension member 12, fulcrumed respectively at the points 2^a and 2^b. The adjustable extension member 12 is held 35 40 within the forked or bifurcated outer end 11² of the member 11 by means of a securing pin 12', which extends through a slotted portion of the member 12 and blocks 12^a slidably mounted in the slotted portions of 45 the said member 11, Figs. 1 and 2 of the drawings. This adjustable operating lever operates respectively the plunger rod 13^a, carrying at its lower end the puncturing awl 13, and the rivet jaw plunger rod 13', 50 each of which extend through and are held within the head 14, slidably mounted within guide ways 14' in the outer enlarged end of the overhang portion of the bracket 2, Figs. 3 and 6 of the drawings. The said 55 slide head is moved outwardly and inwardly for alining the puncturing awl 13 and the rivet jaw plunger rod 13' with the awl opening 15 in the anvil block 15', Fig. 1 of the drawings, fitted in the bed surface 60 65 16 of the base casting 1, by means of the rock shaft 16', which shaft is arranged above and parallel with the operating shaft 3. From the outer end of said rock shaft 16' projects a slotted crank arm 17, within which arm works a stud 17' projecting from

one face of the slide head 14, so as to move the said slide head in accordance with the throw of the rock shaft 16', Figs. 1 and 6 of the drawings. This rock-shaft 16' works within suitable bearings carried by the overhang portion of the bracket arm 2, and from the inner end thereof projects a crank arm 18, from which depends a link 18', pivoted at its lower end to an inwardly projecting lever arm 19. This lever arm at its outer end carries a roll 19', which roll works within an irregular groove 20 cut in one face of the cam 10, and which roll as it travels within said groove 20 serves to raise and lower the lever arm 19 and its link connection 18' to the rock shaft 16', for actuating the same to throw the crank arm 17 for imparting an outward and inward movement to the slide head 14.

From the inner end of the adjustable operating lever fulcrumed to the overhang of the bracket 2, depends a link 21, Fig. 1 of the drawings, which link is pivoted to a lever arm 22, hinged to the base of the machine at an opposite side to that at which the lever arm 19 is pivoted, and, like said arm 19 the lever arm 22 carries a roll 22', which works within an irregular groove 23 cut in the opposite face of the cam 10 to that in which the groove 20 is formed. The said irregular grooves 20 and 23 cut in the opposite faces of the cam 10 are so disposed relative to each other as to properly time the actions of the respective lever arms 19 and 22, for transmitting motion to the described parts controlled thereby, it being understood that as the roll 22' works within the irregular groove 23 it acts to raise and lower the inner end of the fulcrumed operating lever for timing and regulating the movement of the puncturing awl and the rivet receiving and placing mechanism.

The rivet receiving and placing mechanism comprises a clamp jaw consisting of two segmental clamp plates 23 and 23', Fig. 9 of the drawings, which, when brought together, form a mutilated clamp ring, the section removed from the clamp plates providing an opening 24, which permits of the said clamp jaw straddling the lower inwardly curved extension 24' of the rivet runway 25 for the rivets 25', Figs. 5 and 6 of the drawings. From the respective sections of the clamp jaw project the crossed curved arms 26 and 26', which are united by the pivotal pin 27, the free ends thereof being connected and normally held together by means of the spring connection 27'. The pivotal pin 27 extends through a vertical slot 28 formed in the lower reduced end portion of the rivet jaw plunger rod 13', which rod is straddled by the arms 26 and 26'. These arms are forced apart during the inward movement of the slide head 14, to open the clamp jaw for receiving the rivets 25', 130

by means of the cam fingers 28' and 28^a secured to the under face of the portion 29 of the overhang portion of the bracket 2, the free ends of said cam fingers passing respectively between the inner faces of the arms 26 and 26' and the adjustable screw studs 30 and 30' projecting from the outer faces of the slide head 14, the outer crossed extensions 30^a and 30^b being pivoted at 28^a 10 and united by the spring connection 30^c, Figs. 3, 6 and 10 of the drawings.

The connection between the clamp jaw and the plunger rod 13' is a loose one, so that when the clamp jaw bears onto or 15 against the material into the punctured opening of which the rivet is to be inserted, the plunger rod 13', which bears against the head of the held rivet, may continue its downward movement to the extent of the 20 length of the slot 28 therein, Fig. 9 of the drawings, so as to force the rivet 25' from within the cup seat of the clamp jaw and positively force the stem thereof through the perforated material to be riveted. Normally 25 the clamp jaw is held downward its full distance by the pressure of the spring 29' surrounding the reduced end of the plunger rod 13'.

While the clamp jaw when closed onto the 30 head of the rivet 25' exerts sufficient pressure thereon to permit of its ready removal from within the curved extension of the slotted rivet runway 25, such pressure is a slight one and is readily overcome by the 35 downward pressure exerted on the head of the rivet by the plunger rod 13', which forces the rivet from within the clamp, the same giving to such pressure and allowing the held rivet to be forced from within the 40 clamp.

The rivets are placed within a cylindrical container 31, mounted for rotation on a stud 32 upwardly projecting from a fixed plate 32', secured at an inclination to the 45 base of the apparatus, being supported by a bracket 33, Figs. 3, 5 and 6 of the drawings. This supporting plate or disk 32' is formed with a discharged opening 33', situated immediately over the slot of the rivet runway 50 25, and through which the rivets 25' pass. The bottom of the rivet container 31 is formed with a series of peripheral T-shaped outlets 34, through which the rivets escape into the discharge opening 33' of the stationary plate or disk 32' when either of the 55 container outlets 34 register therewith. Within the container is extended a curved guide stripe 34', the purpose of which is to direct the rivets toward the outlets 34 during the rotary movement of the said container, and thus aid the passage of the rivets therefrom.

The rivets 25' as they pass from the container fall onto the runway 25, which comprises two spaced strips, the stem of the

rivets extended through the slot of the runway and the head thereof riding or resting on the upper surface of the said runway, the rivets moving downwardly by gravity until seated on the curved extension 24'. 70 The diameter of the rivet head is slightly greater than the width of the runway and the head projects beyond the side edges thereof, so the same is readily clamped between the jaws of the rivet clamp when 75 closed thereon.

Rotation is imparted to the container 31 by the drive belt 35, which works over the face of the wall of the said container and the pulley 35' on the operating shaft, the 80 said belt passing over the tension rolls 36, Fig. 3 of the drawings.

The washers for the rivets are held within the feed tube 36', which extends through the bed plate of the machine and communicates with the slotted guide way 37, immediately beneath the bed plate, Figs. 6, 11 and 12 of the drawings. Within this guide way works a longitudinally reciprocating feed slide 37', the forward end of which is 85 formed with a semi-circular seat 38 which embraces the lowermost rivet washer 38' of the stack of rivet washers held within the feed tube 36', which rivet washers rests in the guideway 37 immediately in advance of 90 the slide 37'. This guideway 37 for the rivet washers in depth is substantially that of the thickness of a washer, so that a single washer fills the same.

From the slide 37' depends a stud 39 100 which extends and works below the slotted portion 39' of the guide-way 37, and the said stud is connected by a link 40 to the end of the lever 40', the opposite end of which is secured to a vertical shaft 41, to the 105 lower end of which is secured a short arm 42, which, in turn is connected to one end of a horizontal lever 42', the opposite end of which is pivoted to the vertical lever 42^a, carrying roller 42^b, working within an 110 irregular groove 43 cut in the outer face of the cam 10', the upper end of lever 42^a being pivoted to a bearing under the face of the frame, Figs. 6 and 14 of the drawings. As the said roll 42^b works in the groove 43, 115 it actuates the described train of connections to impart longitudinal reciprocation to the slide 37', which, on its outward movement removes the lowermost rivet washer 38' from the stack of washers and carries the 120 same forwardly to the end of the slide's stroke, which is such as to position the said washer onto the tubular rod 44, and in alignment with the needle opening 15 of the anvil block 15', in which position it is held until 125 lifted by the rod 44, after which the slide 37' begins its return stroke. However, on the forward stroke of the said slide 37', it is required that the washers be held in the feed tube 36' or in other words that the 130

lower open end of the tube be closed. This is accomplished by the follower block 44', situated immediately back of the slide 37' and held outwardly pressed by the spring 45, the tension of which acts on the outward or forward movement of the slide 37' to cause the follower 44' to travel therewith and close the lower end of the feed tube 36' when the slide 37' has passed beyond the 10 same. On the inward movement of the said slide, the follower 44' is forced inwardly, compressing the spring 45 so as to act thereon for forcing the same outwardly on the next forward stroke of the slide 37'. The 15 moment the forward end of the slide has passed beyond the discharge end of the feed tube 36' on the return or inward stroke thereof, the stack of retained rivet washers lower by gravity to place a washer within 20 the guide-way 37 in advance of the slide 37'.

The rivet washer is forced upwardly into the awl opening 15 of the anvil block 15' and onto the stem of the rivet extended therein by means of the tubular rod 44, 25 which by a yoke connection 45' is connected to the free end of a pivoted lever arm 46, Figs. 11 and 13 of the drawings. This lever arm carries a roll 46' which works within an irregular shaped groove 47 cut in the 30 inner face of the cam 10², so that as the said cam is rotated the lever arm 46 is swung up and down. As thrown upwardly, it raises the washer holding rod 44 to place the washer held thereby onto the stem of the 35 rivet, in which position it is maintained until the projecting end of the rivet has been upset or headed.

The upsetting of the rivet stem is accomplished by a series of impact blows given 40 unto the loosely held hammer stem 47, which works through the tubular rod 44, the lower end thereof resting upon the hammer head 47' secured to and carried by the free end of a coiled spring 48, Fig. 6 of the drawings. 45 The opposite end of this spring is attached to a rock shaft 48', from which shaft projects an arm 49 carrying a roll 49'. This roll works within a groove 50 in the face of the cam 10² opposite to that containing the 50 irregular groove 47², Fig. 1 of the drawings, and the said groove 50 is formed with the angle sections *a*, *b*, *c*, Fig. 7 of the drawings. As the roll rides outward on angle portion *a* the arm 49 is thrown to actuate the rock-shaft 48' to wind the spring 48 and place the same in tension, the outer end of said spring being held against movement by the pivoted dog 50' which bears thereon, the upper end of the dog being drawn inwardly 55 by the spring 51, but held in proper position by the pawl 52, the position of which may be varied by the adjusting screw 53', Figs. 6 and 7 of the drawings. As the rock-shaft 48' is turned, the outer end portion of the 60 spring 48 is gradually curved or bowed by

restraining influence of the dog 50' to hold the same against upward movement, so that by the time the roll 49' has passed the apex of the angle section *a* of the groove 50, the inner free end 53 of the spring 48 will have 70 been depressed by the bowing or arching thereof to clear the dog 50', Fig. 6 of the drawings, when the torsional strain of the spring 48 will exert itself and the free inner end thereof be suddenly thrown upwardly 75 under heavy pressure, which, carrying the hammer stem 47 therewith causes the upper end thereof to strike against the lower end of the rivet's stem with a severe impact blow. As the roll 49' is carried within the 80 depressed portion of the path of the angle section *a* of the groove 50, the rock-shaft 48' and spring 48 are restored to normal position, the hammer stem 47 lowering therewith. During this movement of the parts, 85 the free end of the spring 48 forces out of its path the lower end portion of the inclined dog 50', so that the moment the same has cleared the lower end of the dog 50', the same springs inwardly to bear onto the 90 upper surface thereof. The described operation takes place as the roll 49' works over the sections *b* and *c*, of the cam groove 50, thus imparting three successive impact blows onto the hammer stem for upsetting 95 or heading of the projecting end of the rivet's stem, the rivet 25' being held down during such action by the plunger rod 13'.

The heading or upsetting of the rivet's stem completes the operation of riveting, 100 when the described parts are again thrown successively into action for the puncturing of the material to be riveted, applying a rivet thereto, a washer on the stem of the rivet and upsetting or heading the stem 105 thereof.

Inasmuch as considerable force is required to extract the awl 13 from within the material 52^a resting on the anvil block 15' after puncturing the same, the upper end of the 110 plunger rod 13^a for the awl 13 is cut away as shown at 13^b, Fig. 6 of the drawings, so that as the member 12 is thrown upwardly, the same engages the under surface of the end 13^c and forcibly lifts the said plunger 115 rod 13^a to withdraw the awl 13 carried thereby from within the material 52^a.

The operation of the apparatus may be briefly described as follows:—As the foot treadle is depressed the clutch or stop rod 120 9' is withdrawn from engagement with the hinged cam shoe 5, when the pressure of the spring 5^b forces the same upwardly and into frictional engagement with the drive pulley 4, thereby imparting the rotation of said pulley to the operating shaft 3. During the rotation of the operating shaft, the cam disk 10 first acts to actuate the rock shaft 16' to throw the slide-head 14 for positioning the awl 13 in alignment with the opening 15 of 125 130

the anvil 15', when the operating lever, comprising the members 11 and 12, is thrown to act against the plunger rod 13^a to lower the awl 13 and cause the same to puncture the material 52 to be riveted. The said plunger-rod 13^a being then raised to withdraw the awl 13, when the rock shaft 16' operates to throw the slide-head 14 to place the rivet clamp in alinement with the opening 15 of the anvil block 15', which clamp has received a rivet 25' from the runway 25. A second stroke is then given to the mentioned operating lever, which lowers the plunger rod 13' to place the stem of the rivet 25' through the punctured material 52, after which the cam disk 10' acts to throw the washer feed slide 37' to place a rivet washer 38' onto the upper end of the tubular rod 44, which rod is raised by the action of the cam 10² to force the washer 38' onto the projecting stem of the rivet 25'. When the washer is so placed, the cam 10² actuates the hammer mechanism to upset the projecting end of the rivet's stem, thus riveting the material. The operating lever is then raised and the plunger rod 13' carrying the clamp jaws restored to normal position by the pressure of the spring 29'. By this time the operating shaft 3 will have made one complete revolution, when, pressure having been released on the treadle 6, the cam shoe 5 will be engaged by the projecting end of the rod 9' and swung downwardly, and out of frictional engagement with the drive pulley, thus releasing the operating shaft and bringing the various working parts to a state of rest. The material 52 is then advanced on the anvil block 15' to position the same to receive another rivet, when the foot treadle 6 is depressed and the described mechanism placed into operation, the parts acting successively during one revolution of the drive-pulley.

It is obvious that various minor changes may be made in the construction of the described working parts without departing from the spirit of the invention, which consists in the providing of means for automatically puncturing the material to be riveted, inserting a rivet therethrough, applying a washer to the projecting stem of the rivet, and finally upsetting the said stem.

Having thus described the invention what is claimed as new and desired to protect by Letters Patent is:—

1. A machine of the class described having in combination an awl for puncturing the material to be riveted, relatively movable clamping jaws for receiving and holding a rivet and associated means for placing the stem thereof through the punctured material, a reciprocating slide adapted to feed rivet washers, a device for forcing a washer onto the stem of the rivet, a hammer for heading the rivet's stem, and automatically actuated mechanism for successively throwing into action the said mentioned instrumentalities.

2. In an apparatus of the character described, the combination of a suitable frame, an operating shaft extended therethrough, a drive pulley loosely mounted thereon, means for placing the same into locked engagement with the operating shaft, an anvil block within the frame, a slide head, a plunger-rod carrying a puncturing awl and a plunger rod carrying a rivet receiving clamp vertically movable within the slide head, devices actuated from the operating shaft for shifting the slide-head for successively alining the puncturing awl and the rivet clamp with the anvil block, and mechanism actuated from the operating shaft for first throwing the awl plunger-rod downwardly to cause the awl to puncture the material and raising the same to extract the awl, and secondly lowering the plunger-rod carrying the rivet clamp to place the stem of a held rivet through the punctured material and holding the same in such position until a washer is applied thereto and the stem headed.

3. In an apparatus of the character described, the combination of a suitable frame, an anvil block held therein, an awl for puncturing the material to be riveted, a device for inserting the stem of a rivet through the punctured material, means for feeding a washer and alining the same with the stem of the rivet, a device movable in the anvil block which latter constitutes a guide, for placing the washer onto the stem of the rivet, and a spring actuated hammer for upsetting the end of the rivet stem, and mechanism for automatically and successively placing into operation the described working instrumentalities.

4. In an apparatus of the character described, the combination of a rivet runway, a rivet clamp for removing rivets from said runway, said clamp including oppositely disposed spring pressed jaws, devices controlling the opening and permitting the closing of said jaws, a puncturing awl, a slide head common to the awl and clamp for operatively positioning the same in turn, and means actuating said clamp to place the rivet carried thereby in the material to be riveted.

5. In an apparatus of the character described, the combination of means for puncturing the cloth to be riveted and inserting a rivet therethrough, of a guide, and devices for forcing a washer through said guide and onto the stem of the inserted rivet, and mechanism for upsetting the projecting end of the rivet, the said guide constituting an anvil block, substantially as and for the purpose described.

6. In an apparatus of the character de-

scribed, the combination with the feed for the rivet washers, of a washer guide having an opening in its side intermediate its ends, a slide for advancing the lowermost washer through said opening and alining the same with the stem of an inserted rivet, devices movable transversely to the slide and through the guide for forcing the washer through the guide and on to the stem, and mechanism for upsetting the projecting end of the rivet stem.

7. In an apparatus of the character described, the combination of a feed for rivet washers, a tubular lift rod for placing a washer onto the stem of an inserted rivet, a hammer stem loosely held in said rod, a spring actuated hammer head acting against the hammer stem, and means for operating the hammer head to impart a series of impact blows onto the hammer stem at predetermined moments during the operation of the apparatus.

8. In an apparatus of the character described, the combination of a suitable frame, an operating shaft working therein, means for imparting rotation thereto, an anvil block secured within the bed of the frame, a slide head held within an overhang of the frame, a puncturing tool and a rivet clamp carried by said slide head, plunger rods for said devices, a rock-shaft for actuating the slide head to alternately place the puncturing tool and the rivet clamp in alinement with the anvil block, a lever for raising and lowering the plunger-rods for said puncturing tool and rivet clamp, a cam on the operating shaft, and connections between said cam and the mentioned rock-shaft for shifting the slide head and the lever for actuating the puncturing tool and the rivet clamp.

9. In an apparatus of the character described, the combination of the rivet clamp comprising two hinged jaw sections, a spring for holding the same normally closed, a plunger rod for said rivet clamp, a spring connection between the plunger rod and the rivet clamp, a rivet runway, means for moving the rivet clamp toward and from the runway, and mechanism for actuating the plunger rod to lower the rivet clamp and apply its held rivet to the punctured material to be riveted, and restore the clamp to normal position.

10. A machine of the character described having in combination a suitable frame, an operating shaft working therein, mechanism for imparting rotation thereto, a reciprocating slide adapted to feed rivet washers, a cam on the operating shaft, and a connection between the feed slide for the washers and the said cam for imparting reciprocating motion to the said slide, a second cam mounted on the said shaft, a plunger movable transversely to the slide for feeding the

washer in a direction transverse to the movement of the reciprocating slide and a member to engage the last mentioned cam having a sleeved connection with the plunger.

11. In an apparatus of the character described, the combination of a reservoir for rivet washers, a feed slide for advancing the washers to the applying devices, a spring held follower movable with the feed slide, and means for imparting a reciprocating stroke to the said slide.

12. In an apparatus of the character described, the combination of a hammer device for upsetting the stem of a rivet, a spring capable of being moved for imparting an impact blow thereto, a spring held dog acting against the free end of said spring, and mechanism for winding said spring to release the same from the dog for acting against the hammer devices.

13. In an apparatus of the character described, the combination of a hammer stem, a spring actuated hammer head acting thereagainst for imparting an impact blow thereto, and means for winding the spring for actuating the hammer head and releasing the same at predetermined moments during the working of the apparatus.

14. In an apparatus of the character described, the combination of a suitable frame, an operating shaft working therein, means for imparting rotation thereto, an anvil block on the bed of the frame, a slide head positioned on the frame above the anvil block, a puncturing tool and a rivet clamp each carried by the slide head, a rock shaft for actuating the slide head to alternately place the puncturing tool and the rivet clamp in alinement with the anvil block, an adjustably supported lever adapted to be operatively connected with the puncturing tool and rivet clamp for raising and lowering the same, a cam on the operating shaft and connections between said cam and the rock shaft for shifting the slide head.

15. In an apparatus of the character described, the combination with an operating shaft, a drive pulley loosely mounted thereon, means for placing the same into locked engagement with the operating shaft, a puncturing awl, a plunger rod carrying the same, pivoted rivet clamping jaws associated with said parts and mounted on the support for the puncturing awl and plunger rod and an adjustable lever thrown into action by the operating shaft for moving the plunger rod, clamping jaws, and the puncturing awl toward and from the material to be punctured.

16. An apparatus of the character described, the same comprising an awl for puncturing the material to be riveted, relatively movable clamping jaws for receiving a rivet and placing the stem thereof through

the punctured material, a common carrying head for the jaws and awl, a reciprocating slide adapted to feed rivet washers, a device for forcing a washer onto the stem of the rivet, a hammer for heading the rivet's stem, and automatically actuated mechanism for successively throwing into action the said mentioned instrumentalities.

17. In a machine of the character described, the combination of an awl for puncturing the material to be riveted, relatively movable clamping jaws for receiving a rivet and placing the stem thereof through the punctured material, a slideable head common to the jaws and awl, a reciprocating slide adapted to feed rivet washers, a device for forcing a washer onto the stem of the rivet, a stationary guide for said device, a hammer for heading the rivet's stem, and automatically actuated mechanism for successively throwing into action the said mentioned instrumentalities.

18. In a machine of the character described, the combination of a horizontally and vertically movable awl for puncturing the material to be riveted, relatively movable clamping jaws, a slide head for positioning either of said parts comprising the awl and clamping jaws, a washer guide and reciprocating slide for delivering rivet washers into the anvil washer guide, a device which works within said guide for forcing a washer onto the stem of the rivet, and a hammer stem loosely held and guided within said washer lifting or forcing device.

19. In a machine of the character described, the combination of a horizontally and vertically movable awl for puncturing the material to be riveted, relatively movable clamping jaws for receiving rivets and holding the same until forced downward into the punctured material, a slide head for moving the awl and jaws into operative position, an anvil-washer guide, a reciprocating slide for feeding rivet washers into the anvil washer guide, a device which works within said anvil washer guide for forcing a washer onto the stem of the rivet, a hammer stem loosely held and guided within said washer lifting or forcing device, and a spring actuated hammer head acting against the hammer stem.

20. In a machine of the character described, the same comprising a horizontally and vertically movable awl for puncturing the material to be riveted, a rivet clamp for receiving rivets and holding the same until forced into the punctured material, a slide head for alternately moving the awl and clamp into operative position, an anvil washer guide, a reciprocating slide for feeding rivet washers into the anvil washer guide, a device which works within said anvil washer guide for forcing a washer onto the stem of the rivet, a hammer stem

loosely held and guided within said washer lifting or forcing device, a spring actuated hammer head acting against the hammer stem, and automatically actuated mechanism for successively throwing into action the said mentioned instrumentalities.

21. In a machine of the character described, the combination of a frame having an overhanging bracket arm, a drive shaft on the frame below the bracket and extending longitudinally of the latter, a head mounted for sliding movement transversely of the bracket, a vertically reciprocating puncturing awl carried by the head, a vertically reciprocating rivet clamp carried by the head, two cam surfaces carried by the shaft, a vertically extending arm having an engagement with one of said cam surfaces, a lever connected intermediate its ends to the bracket and adapted to be operatively connected to the awl and clamp at one end and with the vertical arm at its other end, an auxiliary vertically extending rod operatively connected with the other cam surface, and a horizontally extending rock shaft connected to the auxiliary rod and having a crank connection with the slide head.

22. In a machine of the character described, the combination of a frame having an overhanging bracket arm, a drive shaft on the frame below the bracket and extending longitudinally of the latter, a head mounted for sliding movement transversely of the bracket, a vertically reciprocating puncturing awl carried by the head, a vertically reciprocating rivet clamp carried by the head, plunger rods for the awl and rivet clamp, a double cam surface carried by the shaft, a vertically extending rod having an engagement with one cam surface, a lever extending longitudinally of the shaft and adjustably connected intermediate its ends to the bracket for swinging movement and adapted to be operatively connected at one end to said plungers, and at its opposite end with the vertical rod, an auxiliary vertical rod operatively connected with the other cam face, and a horizontally extending rock shaft connected to the auxiliary rod and having a crank connection with the slide head.

23. In a machine of the character described, the combination of a frame having an overhanging bracket, a drive shaft on the frame below the bracket and extending longitudinally of the latter, a head mounted for sliding movement transversely of the bracket, a vertically reciprocating puncturing awl carried by the head, a vertically reciprocating rivet clamp carried by the head, two cam surfaces carried by the shaft adjacent the outer end thereof, a vertically extending arm having an engagement with one of said cam surfaces, a lever connected intermediate its ends to the bracket and

adapted to be operatively connected to the awl and clamp at one end and with the vertical arm at its other end, mechanism operatively connected to the other cam for 5 sliding said head, a hollow anvil block mounted on the frame below said head, a vertically reciprocating plunger to play through said block, and a cam adjacent the inner end of the shaft having a drive connection with the plunger.

- 10 24. In a machine of the character described, the combination of a frame having an overhanging bracket, a drive shaft on the frame below the bracket and extending longitudinally of the latter, a head mounted for sliding movement transversely of the bracket, a vertically reciprocating puncturing awl carried by the head, a vertically reciprocating rivet clamp carried by the head, 15 20 two cam surfaces carried by the shaft adjacent the outer end thereof, a vertically extending arm having an engagement with one of said cam surfaces, a lever connected intermediate its ends to the bracket, and

adapted to be operatively connected to the awl and clamp at one end and with the vertical arm at its other end, mechanism operatively connected to the other cam for 25 sliding said head, a hollow anvil block mounted on the frame below said head, a vertically reciprocating plunger to play through said block, a cam adjacent the inner 30 end of the shaft having a drive connection with the plunger, a washer runway connecting with the interior of the anvil block 35 above the lower position of the plunger, a reciprocating slide for the washer, and a cam having a drive connection with said slide, said cam being mounted on said shaft intermediate its ends.

40 In testimony whereof I have signed my name to this specification in the presence of two subscribing witnesses.

JAMES E. ARCHER.
